UNITED STATES PATENT OFFICE.

FRED I. THAYER, OF FARMINGTON, NEW HAMPSHIRE.

KNOT SUPPORTER FOR FOUR-IN-HAND NECKTIES.

Application filed December 29, 1926. Serial No. 157,680.

This invention relates to a four-in-hand necktie which is knotted by the wearer in a well known manner. When the tie is worn with a turn-down collar the knot is liable 5 to slip downward after tying, so that there is an unsightly gap between the top portion of the knot and the meeting end portions of the fold of the collar.

Supporters have heretofore been provided 10 to prevent this objection, such supporters being interposed between the usual collar-button engaged with the ends of the collar, and the portion of the knot which is intended to bear on the ends of the fold of the collar. 15 In each instance, so far as I am aware, the supporter has heretofore been undesirably bulky and formed to increase the thickness of the knot from the back to the front side thereof, and cause an objectionable bulging 20 of the front side.

One object of my invention is to provide a supporter which is free from the last-named objection and other objections to knot supporters heretofore used.

25 Another object is to provide a supporter, the knot-engaging portion of which is adapted to conform to the usual inclination of the top portion of the knot as formed by the wearer.

30 Other objects will be apparent as the description proceeds.

Of the accompanying drawings forming a part of this specification,—

Figure 1 is a front view of the knotted portion of a four-in-hand tie as ordinarily formed, and end portions of a turn-down collar, the collar-button and the improved knot supporter being shown by broken lines.

Figure 2 is a rear view of the knotted portion, showing the collar-button and the supporter in the relative positions shown by Figure 1.

Figure 3 is a side view of the supporter by itself.

Figure 4 shows the supporter as in Figure 3, and a collar-button engaged therewith.

Figure 5 is a section on line 5—5 of Figure 4, and shows by broken lines the top portion of the knot shown by Figures 1 and 2.

Figure 6 is a section on line 6—6 of Figure 3.

Figure 7 is a view similar to Figure 3, showing a different form of the supporter.

Figure 8 is a view similar to Figure 7,

showing the preferred form of the supporter for use with soft collars.

Figure 9 is a view similar to Figure 1, showing a soft collar, and by broken lines, the form of support shown by Figure 8. 60

The same reference characters indicate the same parts in all of the figures.

The knot of a four-in-hand tie as usually formed by the wearer, presents the appearance shown by Figure 1, at the front side 65 of the knot, and the appearance shown by Figure 2, at the rear side. The top of the knot is formed by a folded portion 12 of the tie, said portion forming a part of the outer side of the knot, as shown by Figure 70 1, and a part of the inner side, as shown by Figure 2. It is believed that further description of the knot structure is unnecessary.

My improved supporter designated by 75 13, is an oblong piece of suitably stiff and resili- 80 ent sheet material, such as sheet celluloid, although other materials, such as indurated sheet fiber, or thin sheet metal may be em- 85 ployed. The supporter has a slotted end portion formed to be engaged with, and supported by, the shank 14 of a collar-but- 90 ton, at a suitable point between the feet 15 and head 16 of the button, the slot being preferably a button-hole 17, which is en- 95 larged at its midlength portion, and reduced at its end portions, the enlarged portion being adapted to receive the head 16, and the reduced upper end portion to bear on the shank 14, as indicated by Figures 1, 2, 4, 90 5, and 6, so that the shank prevents downward movement of the supporter.

The opposite end portion of the supporter has a knot-engaging edge 19, adapted to bear on the inner surface of the fold 12, as best 95 shown by Figure 5 and preferably serrated as shown.

The user may engage the supporter with the collar-button either before or after forming the knot. When the knot is formed 100 the upper end portion of the supporter is inserted between the rear portion of the fold 12 and the portion of the knot overlapped thereby, as indicated by Figure 2, so that the knot-engaging edge 19 bears on the inner 105 surface of the fold at the top of the knot.

The length of the supporter is such that when its slotted end is engaged with the button shank, its knot-engaging edge is adapted to confine the top of the knot in 110

the end portions of the fold of a turn-down collar 20, engaged with the button. In case the collar is of soft construction, the supporter, acting through the top of the knot, 5 supports the end portions of the fold of the collar, so that they are prevented from sagging.

The thinness of the supporter, the sides of which are substantially flat, although they 10 may be slightly curved, as indicated by Figures 5 and 6, enables the supporter to be located as shown, without adding appreciably to the thickness of the knot from front to rear, so that the supporter does not cause 15 an objectionable bulging of the front side of the knot.

The operation of forming the knot in some cases imparts an inclination to the top of the knot, as shown by Figures 1 and 2. 20 The knot-engaging edge 19 may be inclined, as shown by Figures 1, 2, 3 and 4, to conform to the inclination of the top of the knot. This inclination is advantageous when the supporter is used with a stiff 25 collar. The inclination is omitted in the form shown by Figures 7, 8 and 9, showing the form of stiffener best adapted for soft collars. In this form the upper edge 19 extends substantially at right angles with 30 the longitudinal median line of the supporter, and is somewhat longer than the upper edges of the supporters shown by the other figures, so that its end portions are adapted to extend farther under the ends 35 of the folded-over portion of the collar, as shown by Figure 9, and are of equal height, when the supporter is in use. Said end portions, therefore, prevent the ends of the collar fold from sagging.

40 I also find that the serrations need not be sharply pointed, and may be formed by straight portions of the upper edge, and notches 21 in said edge. The serrations thus formed are not liable to injure the tie.

45 The supporter will be made in different lengths suited to collars of different heights.

It will be seen that the supporter shown and described may be rapidly and inexpensively cut from sheet material by suitable 50 dies.

I claim:

1. A four-in-hand necktie knot-supporter composed of an oblong piece of sheet material having a slotted end portion formed to engage and be supported by a collar-button shank, and an opposite end portion having a knot-engaging edge adapted to bear on the inner surface of the fold constituting the top of the knot as formed by the wearer, the length of the supporter being such that when its slotted end portion is engaged with a collar-button shank, the knot-engaging edge is adapted to confine said top in the end portions of the fold of a turn-down collar engaged with the button, the supporter being adapted also to support said end portions when the collar is of soft construction, the supporter, when in use, being located in the inner side of the knot without adding appreciably to the thickness of the knot from the rear to the front thereof.

2. A four-in-hand necktie knot-supporter composed of an oblong piece of sheet material having a slotted end portion formed to engage and be supported by a collar-button shank, and an opposite end portion having a knot-engaging edge which is inclined relative to the longitudinal center of the supporter, and is adapted to bear on the inclined inner surface of the fold constituting the top of the knot formed by the wearer, the length of the supporter being such that when its slotted end portion is engaged with a collar-button shank, the knot-engaging edge is adapted to conform to the usual inclination of the top of the knot, and confine said top in the end portions of the fold of a turn-down collar engaged with the button, the supporter being adapted also to support said end portions when the collar is of soft construction, the supporter, when in use, being located in the inner side of the knot without adding appreciably to the thickness of the knot from the rear to the front thereof.

In testimony whereof I have affixed my signature.

FRED I. THAYER.
